(57) **CLAIM**

The ornamental design for a pump motor, as shown and described.

DESCRIPTION

FIG. 1 is a front, right side and top perspective view of a pump motor, showing our new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a rear view thereof.

The areas shown in broken lines are included for the purpose of illustrating portions of the pump motor that form no part of the claimed design.
